[57] CLAIM

The ornamental design for a golf putter grip, as shown and described.

DESCRIPTION

FIG. 1 is a perspective view of a golf putter grip showing our new design with a putter depicted in dotted lines for illustrative purposes only;

FIG. 2 is an enlarged top plan view thereof;

FIG. 3 is a left side elevation of FIG. 2;

FIG. 4 is a right side elevation thereof;

FIG. 5 is a front elevation thereof;

FIG. 6 is a rear elevation thereof;

FIG. 7 is an enlarged view taken at the rectangle in FIG. 6; and,

FIG. 8 is an enlarged perspective view of the golf putter grip removed from the putter.

FIG. 1

FIG. 3
